UNITED STATES PATENT OFFICE.

PERKINS E. HOWARD, OF WICHITA, KANSAS.

SPRING-HINGE.

1,027,654.

Specification of Letters Patent.

Patented May 28, 1912.

Application filed December 1, 1910. Serial No. 595,086.

To all whom it may concern:

Be it known that I, PERKINS E. HOWARD, a citizen of the United States, residing at Wichita, in the county of Sedgwick and State of Kansas, have invented certain new and useful Improvements in Spring-Hinges; and I do hereby declare the following to be a full, clear, and exact description of the invention, such as will enable others skilled 10 in the art to which it appertains to make and use the same.

My invention relates to spring hinge, more suitable for screen and barn doors, and has for its object the production of a 15 hinge that will throw the door shut and open as desired.

Another object is to provide means by which greater efficiency or controlling force may be applied to the door without increasing 20 the capacity of the actuating spring.

Another object is to produce a hinge which cannot strain the spring beyond its capacity.

I attain these objects by the mechanism 25 illustrated in the accompanying drawings, in which,

Figure 1, is an end elevation of my hinge. Fig. 2, a plan view. Fig. 3, illustrates my hinge as seen when the door is opened to 30 180 degrees. Fig. 4, when opened to 90 degrees.

Similar numerals refer to similar parts throughout the several views.

1, designates a section of a door jamb or 35 casing. 2, a section of a door.

My hinge is substantially in two sections, 3' and 4' having right angle flanges 3 and 4. Flanges 3 have lateral bends 15. Said 40 flanges and bends are provided with holes to receive pivot-pins 12. The object of the bends 15, is to hold the said pivot pins perpendicular to the plane of the flanges. Flanges 4, are pivotally positioned on the aforesaid pivot-pins, these hinge sections

45 are fastened to the door jamb and door with screws 19. On pins 12 are pivotally positioned yokes 5, in the free ends of said yokes are pivot-pins 11. Similar yokes 6 are pivotally mounted astraddle of the 50 flanges 3 and pivotally affixed thereto with a rod 9. Links 7 and 8 are placed on the pivot-pins 11, the ends of links 7 have lateral bends 14 and are provided with holes to receive the rod 10, the outer ends of the

links 8 are pivotally attached to the flanges 55 4 by a rod 13, between said rods and flanges are washers 22, the object of the said washers and bends 14 are to keep the said links parallel to the flanges 3 and 4. To section 4' is affixed a plate 18 with screws 20. Said 60 plate being provided with a pierced lug 17, and a spiral spring 16 is hooked in said lug and to the rod 10. It is obvious that if the hinge section 4' is extended out farther on the door, the closure of the door would be 65 effected with less spring power, it is apparent that the spring exerts its force from both ends, a part of its force being applied to the links 7 and 8 which closes and holds the door shut, but when the door is opened 70 to 180 degrees the links are out of commission and the spring force is exerted on the lug 17 which continuously holds the door open. It is further noted that when the door is closed it is continuously spring 75 pressed, and when opened to 90 degrees the spring assumes a neutral attitude, but when opened beyond 90 degrees the spring immediately becomes effective and throws the said door open to 180 degrees and again it 80 is spring pressed. Hence, I have a hinge which is substantially double acting.

What I claim is:—

1. In a hinge comprising two sections, 85 each section having perpendicular flanges pivotally connected, pins pivotally uniting said section, yokes pivotally mounted upon said pins, yokes embracing the flanges of one hinge section and pivotally connected thereto, links having lateral bends pivotally connected to the last named yokes, their other ends being embraced in the aforesaid yoke members and pivotally connected thereto, links pivotally connected to the other hinge section, their other ends pivotally connected to the pivots of the aforesaid yokes. 95

2. In a hinge comprising two sections, 100 each section having perpendicular flanges pivotally connected, pins pivotally uniting said section, yokes pivotally mounted upon said pins, yokes embracing the flanges of one hinge section and pivotally connected thereto, links having lateral bends pivotally connected to the last named yokes their other ends being embraced in the aforesaid yoke members and pivotally connected thereto, links pivotally connected to the 105

other hinge section, their other ends pivotally connected to the pivots of the aforesaid yokes, a plate having a perpendicular pierced lug, and a spring to close the door
5 when opened less than 90 degrees and to actuate the door when opened more than 90 degrees.

In testimony whereof, I have signed this specification in the presence of two subscribing witnesses.

PERKINS E. HOWARD.
